UNITED STATES PATENT OFFICE

155,945

DESIGN FOR A RING DISPLAY BOX

Samuel Tylon, Cleveland, Ohio

Application March 15, 1948, Serial No. 145,100

Term of patent 3½ years

(Cl. D58—11)

To all whom it may concern:

Be it known that I, Samuel Tylon, a citizen of the United States of America, residing at Cleveland, in the county of Cuyahoga and State of Ohio, have invented a new, original, and ornamental Design for a Ring Display Box, of which the following is a specification, reference being had to the accompanying drawing, forming a part thereof.

In the drawing:

Figure 1 is a top plan view of a ring display box, embodying my new design.

Figure 2 is a bottom plan view of the same.

Figure 3 is a side elevational view thereof, the other side being similarly ornamental.

Figure 4 is a front elevational view of the same.

Figure 5 is an enlarged sectional view thereof as taken on line 5—5 of Figure 1.

I claim:

The ornamental design for a ring display box, as shown and described.

SAMUEL TYLON.
